UNITED STATES PATENT OFFICE.

JOHN DAHLQUIST, OF NEWPORT NEWS, VIRGINIA.

TALKING MACHINE.

Application filed December 3, 1920. Serial No. 428,085.

To all whom it may concern:

Be it known that I, JOHN DAHLQUIST, a citizen of the United States, residing at Newport News, in the county of Warwick 5 and State of Virginia, have invented certain new and useful Improvements in Talking Machines, of which the following is a specification.

My invention relates to talking machines 10 or phonographs, and more particularly to the construction and arrangement of the horn and modifier relatively to each other and to the motor board with which they co-operate.

15 My object is to provide a device of this character of very simple, cheap and durable construction, that will be thoroughly effective in operation.

20 Other and more specific objects will appear in the subjoined description.

An important feature of my invention 25 consists of a horn provided at its inner open end with means for securing it to the motor board, said means consisting of two flat bars disposed parallel to each other and secured at their lower edges to opposite sides 30 of the extreme upper end of the horn, and bent outwardly at their outer ends to form openings or holes for the reception of screws for securing the horn to the motor-board, said bars being of sufficient width 35 to provide room between the top of the horn proper and the motor-board for the insertion of a modifier or damper to regulate the volume of sound delivered by the horn.

The invention consists in certain novel 40 features of construction and arrangements of parts as will be hereinafter described and claimed, reference being had to the accompanying drawings in which;—

Fig. 1 is a side elevation of the upper part of a phonograph embodying my invention, the cabinet and certain other parts being shown in section to more clearly bring 45 out the construction.

Fig. 2 is a perspective view of the frame of my horn.

Fig. 3 is a perspective of the modifier or damper.

50 Fig. 4 is a broken perspective showing the damper in its normal position relatively to the two securing bars at the inner end of the horn.

Fig. 5 shows a slightly modified form of 55 securing bars at the upper end of the horn.

Fig. 6 is a top plan view of my phonograph with the dome removed.

Fig. 7 is a side elevation of the horn; and,

Fig. 8 is a bottom plan view thereof.

Referring further to the drawings, the numeral 1 indicates the cabinet; 2, the dome; 3, the motor-board; 4, the motor; 5, the record; 6, the reproducer; and 7, the tone arm. All of these parts just mentioned are 60 of usual or any preferred construction.

The horn of my device is formed of fabric or flexible material supported by a wire frame, the frame usually being on the outside of the fabric.

70 The frame of the horn is formed of the upper and lower longitudinal wires 8 and 9 respectively, which form the four longitudinal corners, so to speak, of the horn. These wires are connected together by means 75 of the substantially rectangular wire frames 10, 11, 12, 13 and 14, which are secured at their corners by soldering or any other preferred means to the upper and lower corner wires 8 and 9. The rectangular frames 10 and 14 are at the inner and outer ends respectively of the horn. The top and bottom sections of the rectangular frame 14 are connected between their ends to the upper and lower corners respectively of the frame 80 13, by means of the brace-rods 15, which rods are also secured at their ends to said parts by solder or otherwise. At the extreme outer end of the horn the wires 8 and 9 extend outwardly slightly beyond the rectangular frame 14 to form the extension 85 8^a and 9^a respectively.

90 Special attention is now called to an important feature of my construction. At the inner end of my horn are two flat bars 16, 95 with their lower edges secured to the outer and inner sides respectively of the rectangular frame 10, and bent outwardly at their ends into the circular loops 17 to form the holes 18 for the reception of screws for securing the horn to the motor-board.

100 The damper or modifier 19 is received on top of the frame 10 between the two flat parallel bars 16, and is adapted to move longitudinally back and forth between said 105 bars, said modifier having a central opening 20 adapted to be moved into registration with the opening 21 in the motor-board, which latter opening leads up into the tone arm 7 above the motor-board.

The modifier 19 is provided with a handle 22 which projects out through the side of the casing 1, and is provided with a ball or knob 23 on its outer end.

5 A slightly modified form of my horn is illustrated in Fig. 5, in which the flat bars 16 are substituted by wires 24, which are bent at their ends to form the round loops 25 for the reception of screws for securing 10 the horn to the motor-board. This form of the horn is for machines that do not have a modifier.

The flexible part of my horn which is supported by the wire frame, is formed of any 15 desired material, such for instance, as silk, muslin, burlap, canvas, and the like; and these fabric materials may be treated in any ordinary or preferred way, in order to improve the quality of the tone produced or 20 the durability of the horn. The horn is secured to the frame in any desired way, and usually on the inside thereof.

In operation the inner end of the horn is secured to the under side of the motor 25 board 3 immediately underneath the tone arm, by means of screws passed up through the openings 18 of the flat bars 16; and the projections 8^a at the outer end of the horn are received in the corners of the opening 30 26 in the front side of the cabinet.

The modifier is received between the inner open end of the horn and the under side of the motor board, between the two bars 16 which hold it against lateral movement,

while the handle 20 extends out through a 35 suitable opening in the front side of the cabinet, which arrangement permits the operator of the machine to move the modifier longitudinally back and forth, to bring its opening 20 into different degrees of registration with the opening 21 in the motor board. 40

In the modified form of the device illustrated in Fig. 5, the securing screws are passed through the circular loops 25, by which arrangement the inner end of the horn 45 is secured to the motor board without any intervening space between.

From the foregoing it will be seen that I have provided a horn of very simple and cheap construction, which also forms a support or housing for the modifier. 50

Having now described my invention, what I claim as new and desire to secure by Letters Patent is:—

In a device of the character described, a 55 horn having a supporting frame suitably secured around the outside thereof, said frame being provided at its inner open end with transversely disposed parallel spacing bars rigidly secured thereto for holding the horn 60 in spaced relation to the motor board, said spacing bars being bent outwardly at their ends into circular loops to form holes, whereby to provide means for securing the horn to the motor board. 65

In testimony whereof I affix my signature.

JOHN DAHLQUIST.
